UNITED STATES PATENT OFFICE.

MARTIN J. SHAUGHNESSY, OF AMSTERDAM, NEW YORK.

KNITTED FABRIC.

No. 806,926.

Specification of Letters Patent.

Patented Dec. 12, 1905.

Application filed July 24, 1905. Serial No. 270,966.

To all whom it may concern:

Be it known that I, MARTIN J. SHAUGHNESSY, a citizen of the United States, residing at Amsterdam, county of Montgomery, and 5 State of New York, have invented certain new and useful Improvements in Knitted Fabric, of which the following is a specification.

The invention relates to such improvements; and it consists of the novel construction 10 and combination of parts hereinafter described and subsequently claimed.

Reference may be had to the accompanying drawing, and the reference characters marked thereon, which form a part of this specification.

Similar characters refer to similar parts in the figure.

The single figure of the drawing is a view 20 on a greatly-enlarged scale of a piece of knitted fabric embodying my invention.

The invention relates to open-meshed knitted fabrics, such as are formed by transferred stitches in the knitting operation.

The principal objects of the invention are 25 to reinforce and give body to such a fabric, to enable the same to maintain its knitted shape, and to give a more symmetrical form to the meshed openings or apertures left by the transfer of certain stitches from one needle to another in the knitting operation.

Referring to the drawing, I have shown at 1 1 ordinary knitted loops or stitches of which the principal portion of my improved fabric is composed.

To render the fabric more open or porous, 35 I at intervals in the knitting operation transfer a stitch from one needle to another, such transferred stitches being shown at 2 2, the result being to produce in the knitted fabric 40 an aperture 3.

The transferring of the stitches may be accomplished in any known manner, and by adapting the transferring mechanism to transfer certain predetermined stitches various 45 ornamental patterns of openwork fabric may be produced, as is well understood by those skilled in the art.

In proceeding with the ordinary knitting after the transfer of a stitch the thread forming 50 the next following course of stitches would stretch without intermediate support from one of the last previously-knitted untransferred loops or stitches to the second loop or stitch formed in the same course, 55 tending to produce a somewhat slazy fabric and giving to the interstices or aperture left

by the transferred stitch a contracted unsymmetrical form due to the stretching of said thread in a comparatively straight line across the lower end of said opening.

60

To improve the firmness or body of the fabric, as well as the appearance of the same, I form in the knitting operation immediately below each aperture left by a transferred stitch a tuck-stitch or double stitch, whereby 65 the thread in the course immediately beneath said aperture is paralleled and reinforced by the thread of the second course below said aperture, and the thread of said first course below said aperture is stretched and drawn 70 out of a straight line by the intermeshing therewith of a loop in the thread of the third course below said aperture.

Referring more particularly to the drawing, 4 represents the thread in the next course 75 below the transferred stitch, which if not formed into a tuck - stitch would extend, as indicated by the dotted lines 5, in a substantially straight line across the lower end of said aperture left by the transferred stitch, thereby greatly diminishing the size of said aperture.

As shown by solid lines, however, said thread forms a loop 6, extending parallel with a loop 7 in the thread 8 of the next following course and is intermeshed with loop 9 of the 85

thread 10 of the second following course, which loop 9 in the operation of ordinary 90 knitting would interlock with the loop 7 of the thread in the course 8. The pull exerted by the loop 9 upon the loop 6, due to

the elasticity of the fabric, draws the loop 6 downwardly to enlarge and make more symmetrical the aperture 3, while the extending of the loops 6 and 7 parallel with each other 95 serves to reinforce and give body to the fabric at a point immediately below said aperture, rendering the aperture less liable to be distorted and drawn out of shape by a stretching of the fabric.

The doubling up of the stitches or loops 6 100 and 7 forms what is known in the art as a "tuck-stitch" and is accomplished by the use of a cut-presser to act upon the thread 5, said presser being cut to receive and not close the beard of the needle from which the stitch has just previously been transferred, so that said 105 stitch, which is the stitch 6, (shown in the drawing,) is left upon the needle and not cast off, and when the thread 8 of the next feed or course is fed to said needle said needle will 110 then have two loops or stitches thereon which are the loops or stitches 6 and 7 and which

are subsequently cast off by a presser and cast-off mechanism, all in the manner well understood in the art.

The drawing being on an enlarged scale and 5 more or less diagrammatic in character causes the opening 3 to assume a very irregular form. In practice, however, this opening in the fabric, made in accordance with my invention, is substantially circular and symmetrical.

10 What I claim as new, and desire to secure by Letters Patent, is—
A knitted fabric having a transferred stitch,

and immediately below the space caused by said transferred stitch, a loop in the first course thereafter, and a loop in the second 15 course thereafter, both intermeshed with the same loop in the third course thereafter.

In testimony whereof I have hereunto set my hand this 20th day of July, 1905.

MARTIN J. SHAUGHNESSY.
